(57) **CLAIM**

The ornamental design for a “convertible electronic device,” as shown and described in FIGS. 1-13.

DESCRIPTION

FIG. 1 is a right, front perspective view of a convertible electronic device with a keyboard in a first stowed position. FIG. 2 is a front view of the convertible electronic device of FIG. 1.

FIG. 3 is a rear view of the convertible electronic device of FIG. 1.

FIG. 4 is a top view of the convertible electronic device of FIG. 1.

FIG. 5 is a bottom view of the convertible electronic device of FIG. 1.

FIG. 6 is a right side view of the convertible electronic device of FIG. 1.

FIG. 7 is a left side view of the convertible electronic device of FIG. 1.

FIG. 8 is a right, front perspective view of the convertible electronic device of FIG. 1 with the keyboard in a first deployed position.

FIG. 9 is a front view of the convertible electronic device in the position of FIG. 8.

The rear view of the convertible electronic device in the position of FIG. 8 is the same as shown in FIG. 3.

FIG. 10 is a top view of the convertible electronic device in the position of FIG. 8.

FIG. 11 is a bottom view of the convertible electronic device in the position of FIG. 8.

FIG. 12 is a right side view of the convertible electronic device in the position of FIG. 8; and,

FIG. 13 is a left side view of the convertible electronic device in the position of FIG. 8.

The features shown in broken lines form no part of the claimed design.

Any features of any figure may be combined with any other features of any other figure.

1 Claim, 13 Drawing Sheets
